UNITED STATES PATENT OFFICE.

JULIUS H. HOLMGREEN, OF SAN ANTONIO, TEXAS.

METHOD OF CASTING THE HULLS OF SHIPS FROM CONCRETE AND FLOATING SAID HULLS INTO A LAUNCHING-BAY.

1,383,117.

Specification of Letters Patent. Patented June 28, 1921.

Application filed October 5, 1918. Serial No. 257,053.

To all whom it may concern:

Be it known that I, JULIUS H. HOLMGREEN, a citizen of the United States, residing at San Antonio, in the county of Bexar 5 and State of Texas, have invented certain new and useful Improvements in Methods of Casting the Hulls of Ships from Concrete and Floating Said Hulls into a Launching-Bay, of which the following is a 10 specification.

This invention relates to a novel method of molding or casting the hulls of ships and other floating craft from concrete or suitable plastic material.

15 The object of the invention is to facilitate and expedite the construction of concrete hulls by casting the hull in a permanent mold or form and subsequently releasing the hull from the mold by hydrostatic 20 means and floating said hull into the launching bay or channel.

A further object is to provide a method, in 25 the practice of which, the employment of scaffolding around the exterior of the form or mold is rendered unnecessary and the use 30 of "ways" for launching the hull after completion is entirely dispensed with, thereby materially decreasing the cost of construction and increasing the output or production.

35 The invention further contemplates the prevention of fracture of either the form or hull of the vessel by providing for the uniform elevation of the hull on an even 40 keel within the mold during the floating operation.

A further object in view is the provision 45 of a surfacing lining between the mold and the bottom of the hull, said lining being 50 perforated to permit the passage of water and being displaced by the action of said water during the floating operation.

The method consists, generally stated, in 55 constructing a mold or form *in situ*, preferably lining the bottom of the mold with surfacing material, casting the hull within 60 the mold, introducing water preferably through the bottom of the mold and through 65 said lining to displace the latter, and causing 70 water to float the molded or cast hull out of the mold and into a receiving dock, discharging the water from the dock to 75 lower the hull therein and permit the application of an exterior finish thereto, and

subsequently floating the finished hull from 55 the dock into the launching bay or channel. Other and incidental objects will appear as the description proceeds. In the drawings, wherein I have illustrated the preferred embodiment of the invention, and 60 wherein similar reference characters designate corresponding parts throughout the several views:

Figure 1 is a longitudinal sectional view of the apparatus employed in carrying the 65 improved method into effect, showing the initial step or casting operation.

Fig. 2 is a similar view showing the cast or molded hull released from the mold in position to be floated into the receiving 70 dock,

Fig. 3 is a longitudinal sectional view showing the hull within the receiving dock and ready to be floated into the launching 75 bay or channel,

Fig. 4 is a top plan view of Fig. 1,

Fig. 5 is a transverse sectional view taken on the line 5—5 of Fig. 4, and showing the means for maintaining the hull on an even keel when floating the hull vertically within 80 the molding chamber,

Fig. 6 is a transverse sectional view on the line 6—6 of Fig. 4 and showing the hull supported on keel blocks within the receiving dock preparatory to applying the exterior finish thereto, and

Fig. 7 is an enlarged transverse sectional view showing the construction of the surfacing lining and the manner of admitting water thereto.

Similar numerals of reference indicate 90 corresponding parts in all the figures of the drawings.

For the sake of illustration and for the further purpose of enabling those skilled in 95 the art to readily construct a concrete hull in accordance with my improved method, I have shown and described a mold or apparatus capable of carrying the method into effect, but it may be here stated that said 100 mold or apparatus and its associated parts form the subject matter of a separate application, executed of even date herewith, and that no claim is made in this application thereto, the present invention being confined to the novel method of constructing 105 and floating the hull.

The apparatus employed in carrying out

the improved method comprises an outer mold or form 5 preferably formed of concrete and built *in situ* at a point convenient to the launching bay or channel, said mold including inner and outer walls 6 and 7, spaced apart to form a circumferential chamber or passage 8 as shown.

The inner wall 6 of the outer form is of the shape or configuration of the hull 8' to be cast and is provided at the bottom of the mold and for a short distance up the sides thereof, with transverse openings 9 which communicate with the chamber 8 and through which water is admitted for the purpose of floating the hull to release the same from the form or mold, as will be more fully explained hereinafter.

The openings 9 are normally closed by a strip or layer of wire netting or other fo- 20 raminous material 10, which is temporarily secured to the inner surface of the inner wall 6 and is covered by a thin sheet metal plate 11 and one or more sheets or layers of waterproof paper or similar material 12, the 25 wire netting terminating a short distance above the bottom of the mold and the paper being extended the entire height of the mold as best shown in Fig. 7 of the drawings. The layer or layers of paper 12 form the finish- 30 ing surface for the adjacent face of the mold and serve to prevent the cement from adhering thereto during the molding or casting operation, while the wire netting permits the water to pass through the openings 9 and 35 back of the layers of paper so as to dislodge the same when water is admitted to the chamber 8 to effect the hydrostatic release of the hull from the mold.

The outer walls of the mold are preferably 40 extended longitudinally to form a receiving dock 13 which is separated from the mold by a transverse bridge wall 14 having openings 15, therein communicating with the interior of the dock and through which water 45 is admitted and discharged for the purpose of filling or emptying the dock. A suitable gate 16 forms a closure for the rear end of the receiving dock and, as shown in Fig. 3 of the drawings, the bottom of the dock is 50 preferably disposed below the low tide sea level so that after the exterior of the hull has been coated or otherwise finished and the gate 16 opened, the hull may be floated out of the dock into the launching bay or 55 channel, thus dispensing with "ways" usually employed for launching ships and other floating craft.

The upper portion of the wall 6 of the mold is preferably offset to form a walkway 60 17 and is thence extended upwardly above the top of the bridge wall so as to permit the water to flow from the molding chamber over said bridge wall into the receiving dock and consequently permit the hull, after 65 being formed in the mold, to be floated to

a position over the receiving dock. It will, of course, be understood that an inner form or shell (not shown) will be employed in conjunction with the outer form in molding or casting the concrete hull, but as the mechanical construction of the mold and receiving dock forms the subject matter of a separate application, further detailed description thereof is deemed unnecessary.

In carrying out the improved method, the 70 wire netting, metal plate and paper strips are temporarily secured to the inner wall of the outer form in the manner shown in Fig. 7 of the drawings, after which the inner form or shell is positioned in spaced relation thereto and the concrete poured, shoveled or otherwise introduced between said forms and allowed to stand until thoroughly set or solidified. If desired, the concrete after being introduced into the mold- 75 80 85 90 95 100 105 110 115 120 125 130 135 140 145 150 155 160 165 170 175 180 185 190 195 200 205 210 215 220 225 230 235 240 245 channel. The gate 16 is then closed and the pump 18 operated to discharge the water from the mold and receiving dock when the former will be in condition to again be used 5 for casting a concrete hull.

By the practice of the method forming the subject matter of the present invention, the employment of scaffolding around the exterior of the mold is rendered unnecessary 10 and the use of "ways" for launching the hull after completion is entirely dispensed with, thereby not only materially decreasing the cost of construction but also increasing the output or production. Furthermore, inasmuch as the hull is floated out of the form or 15 mold and floated onto the waters of the launching bay or channel, liability of cracking, straining or otherwise injuring the hull during transition to the launching waters is reduced to a minimum so that the completed 20 hull will possess maximum efficiency.

The outer form, being permanent or stationary and of a size capable of making standard sized hulls, may be used over and over again without any special attention on the part of the workmen and without the necessity of knocking down the form and subsequently assembling the parts each time a hull is cast, as is the case with molds now 30 in general use for this purpose. If desired, the mold, instead of being constructed on the shore near the launching bay or channel, may be formed in or as part of a floating dock, in which event the submergence 35 or partial submergence of the dock in the water will effect the floating of the cast or molded hull within the mold to a position level with the surface of the water so that said hull may be floated out of the dock, as 40 will be readily understood.

Having thus described the invention, what is claimed as new is:

1. The method of constructing the hulls of ships from concrete which consists in 45 covering the bottom of a suitable mold having perforations in its lower part with a lining of paper, casting the hull within the mold and subsequently introducing water through perforations in the mold to disintegrate the lining and float the hull out of the 50 mold.

2. The method of constructing the hulls of ships from concrete which consists in casting the hull in a mold form, introducing water 55 through perforations in the form to float the cast hull out of the form without destroying the integrity of said form, floating the cast hull into a receiving dock adjacent the form containing water, discharging the 60 water from the dock to expose the exterior of the hull to permit the application of an

exterior finish thereto, and subsequently floating the finished hull out of the dock into a launching bay or channel.

3. The method of constructing the hulls 65 of ships from concrete which consists in arranging a suitable mold form and receiving dock in juxtaposition to each other, casting the hull in the mold form, introducing water through perforations in the mold form to 70 float the hull out of said form and at the same time admitting water into the receiving dock, floating the hull from a position directly over the top of the form to a position within the receiving dock, discharging 75 the water from said dock to expose the exterior of the hull and permit the application of finishing material thereto, and subsequently admitting water into the receiving dock to float the hull into a launching bay 80 or channel.

4. The method of constructing the hulls 85 of ships from concrete which consists in arranging a suitable mold form and receiving dock in juxtaposition to each other, casting the hull within the form, admitting water into the receiving dock and between the form and hull to float the hull out of said form and to a position within the receiving dock without disturbing the integrity of the form, 90 discharging the water from within the receiving dock to expose the hull and permit the application of an exterior finish thereto, and subsequently admitting water at low tide sea level within the receiving dock to 95 float the hull into a launching bay or channel.

5. The method of constructing the hulls 100 of ships from concrete which consists in casting the hull in a mold form, releasing the cast hull from the form by hydrostatic means and causing the hull to rise to the top of the mold on an even keel without disturbing said form, floating the hull into a receiving dock filled with water, discharging the water from the receiving dock to expose 105 the entire body of the hull for the application of an exterior finish, and subsequently admitting water into the receiving dock to float the finished hull into a launching bay 110 or channel.

6. The method of constructing the hulls 115 of ships from concrete comprising the casting of the hull in a mold form, introducing water between the mold form and the hull to float the hull out of the form, floating the hull into an adjacent receiving dock filled with water and discharging the water from the receiving dock to expose the entire body of the hull, substantially as set forth. 120

In testimony whereof I affix my signature.
JULIUS H. HOLMGREEN. [L. S.]
